McWilliams, Sweeney & Ohlson**[57] CLAIM**The ornamental design for a thermostatic expansion
valve for refrigerating plants, as shown and described.**DESCRIPTION**FIG. 1 is a perspective view of a thermostatic expansion
valve for refrigerating plants according to my invention;

FIG. 2 is a perspective view opposite to that of FIG. 1;

FIG. 3 is a top plan view thereof;

FIG. 4 is a bottom plan view thereof;

FIG. 5 is a front elevational view thereof;

FIG. 6 is a rear elevational view thereof;

FIG. 7 is a side elevational view thereof; and,

FIG. 8 is a side elevational view thereof opposite to
FIG. 7.FIGURE 1
